CUTTING DEVICE FOR WIRE CLOTH

Filed Jan. 6, 1926

Fig. 1.

UNITED STATES PATENT OFFICE.

CHARLES M. McCARTHY, OF MINNEAPOLIS, MINNESOTA.

CUTTING DEVICE FOR WIRE CLOTH.

Application filed January 6, 1926. Serial No. 79,700.

This invention relates to a device for handling flexible sheet material and particularly such material as wire screen or cloth. The invention is especially directed to a means for dispensing such material from a roll and cutting off the material when the desired length has been dispensed. Wire screen and cloth is now sold in many retail stores and is kept in stock in rolls. It is necessary to have a large number of rolls of various sizes and it has heretofore been an inconvenient procedure to dispense this material. Applicant has invented a rack on which the rolls of material may be carried and the present invention is especially adapted to be used in connection with said rack and to greatly facilitate the dispensing of the material.

It is an object of this invention to provide a simple and efficient means for engaging and drawing from a stock roll a certain length of material and quickly and conveniently severing the desired amount of material.

It is a further object of the invention to provide a device comprising a revoluble means with which the material may be engaged and on which it may be rolled as it is drawn from the stock roll, together with a stationary cutting member over which the material is drawn having a movable cutter cooperating therewith which can be moved to sever the material.

It is a further object of the invention to provide a device, as set forth in the preceding paragraph, together with means for holding the material properly positioned while it is being dispensed.

These and other objects and advantages of the invention will be fully set forth in the following description made in connection with the accompanying drawings in which like reference characters refer to same parts throughout the several views, and in which,

Fig. 1 is a plan view of the device;

Fig. 2 is a view in side elevation shown on a somewhat enlarged scale;

Fig. 3 is a view in front elevation of a portion of the cutting device used;

Fig. 4 is a view in vertical section taken on the line 4—4 of Fig. 3, as indicated by the arrows;

Fig. 5 is a view in end elevation of a portion of the device, shown on an enlarged scale;

Fig. 6 is a vertical section taken on the line 6—6 of Fig. 5, as indicated by the arrows;

Fig. 7 is a vertical section taken on the line 55 7—7 of Fig. 1, as indicated by the arrows; and

Fig. 8 is a horizontal section taken on the line 8—8 of Fig. 2, as indicated by the arrows.

Referring to the drawings, a device is shown comprising spaced vertical members 10. While these members may take various forms, in the embodiment of the invention illustrated, they are shown as angle bars 65 having their angles directed inwardly, and said members may form the vertical sides of a rack adapted to carry rolls of flexible material, such as wire cloth or wire screen. Rigidly secured to each of the members 10 at 70 their outer sides and projecting forwardly therefrom are the short arms 11 also illustrated as formed of angle bars, the top horizontal webs thereof being cut away at their forward ends, which ends are pierced by the 75 headed and nutted bolts 12 also passing through the forwardly extended arms 13 which are thus pivotally connected to the arms 11. The arms 13 can thus swing downwardly to vertical position at the ends of arms 11. The 80 arms 13 may be held in substantially horizontal position by means of the member 14 rigidly secured at its upper and rear end to one of the standards 10 and extending downwardly and forwardly and having a hook 85 portion 14^a at its lower end adapted to hook over an inwardly projecting pin 15 secured in one of the arms 13. One of the arms 11 has a U-shaped member 16 secured thereto, the upwardly extending spaced arms of 90 which are pierced by and form a bearing for one end of a rod 17 having a cotter pin 18 passing therethrough between the arms of member 16 to hold the same in position. The rod 17 extends outwardly from the member 16 and is bent at substantially a right angle to extend forwardly parallel to the arm 13 and then again bent substantially at a right angle and extends inwardly over the top of arms 13 having secured to its terminal 95 100 a coupling collar 17^a. A tensile spring 18 is secured to the forward end of one arm 11 and at its other end to the arm 17 tending to swing the forward portion of said arm downwardly. A member 19, preferably, 105 formed of flat material similar to the member 14, is rigidly secured to one of the standards 10 beneath said member 14 and by the same

fastening means which secures the upper end of arms 14. The member 19 also extends downwardly and forwardly beneath member 14 and is formed with two recesses 19^a and 19^b, respectively, adjacent its lower end, either of which is adapted to hook over the inwardly extending portion of rod 17. A measuring device designated as a whole as 20 has a laterally projecting shaft 20^a which 10 is secured in the coupling 17^a, and said measuring device has a knurled friction drum 20^b. The friction drum 20^b is disposed over and adapted to co-operate with a roller 21 journaled in bearings in a plate 21^a projecting 15 rearwardly from one of a pair of angle bars 22, which angle bars 22 are secured to and extend between the spaced arms 13. The angle bars 22 constitute a stationary cutting means and, as shown in Figs. 2, 4 and 5, said 20 bars 22 are disposed with their vertical portions adjacent and slightly spaced. Secured between the bars 22 at each end thereof and extending upwardly therefrom above arms 13 is a bracket 23 preferably formed of a flat 25 piece of material having its upper end shown as offset slightly and reversely bent at right angles to provide spaced parallel portions 23^a. A bar 24 shown as comprising a flat strip of material extends between the brackets 30 23 having its ends disposed between the parallel portions 23^a and having vertical slots 24^a at its ends through which pass rivets or bolts 25 secured in the portions 23^a. A compression spring 26 is disposed beneath the 35 top portion of each bracket 23 and the top edge of bar 24, said springs normally tending to force said bar downwardly. A movable cutter carrying member 27 is provided formed of a plate of general rectangular 40 shape bent at its central portion to have its sides disposed in slightly spaced parallel relation with a semi-cylindrical portion 27^a at its central bent portion. Said member 27 has a pair of rollers 28 journaled between its 45 sides portions on suitable rivets or bolts 29 and said member also has a disk cutter 30 journaled centrally thereof at its lower portion on the rivet or bolt 31, which cutter projects below the lower edge of member 27 and 50 between the upper ends of the bars 22. As shown in Figs. 2, 3 and 4, the bar 24 extends between the sides of member 27 above the rollers 28 and is normally forced down against said rollers by the springs 26. The 55 semi-cylindrical top portion of member 27 forms a convenient handle by which said member may be moved transversely.

An elongated roller 32 is journaled on a rod 33 extending above and between the arms 60 13, said rod having its ends bent downwardly substantially at a right angle and extending through the horizontal flanges of arms 13, said ends being secured in said arms by nuts threaded on their ends. The rod 33 has 65 collars 33^a thereon engaging the top of the

arms 13. The roller 32 is held in position lengthwise by the collars 34 pinned to the rod 33 at the ends of said roller.

The forward ends of arms 13 at the left of Fig. 1 has an aperture formed therein adapted to receive one end of a longitudinally split shaft 35. The other arm 13 has its horizontal flange cut away and a vertical flange formed with an open ended socket 13^a. A plate 36 is mounted on top of the horizontal flange of said latter arm 13 and has an elongated slot 36^a therein through which pass the headed and nutted bolts 37 secured in the arm 13, the plate 36 being adapted to extend over the socket 13^a and having its front end bent slightly upwardly to form a finger-piece or operating means. The socket 13^a receives the other end of split shaft 35. The outer end of shaft 35 is not split and formed as a crank 35^a having thereon the handle 38. One section of the shaft 35 is secured to one half 39^a of a roll 39 and the other half of shaft 35 is secured to the other half 39^b of said roll, said roll 39 extending between the arms 13. Tensioning arms 40 are provided having flat curved front portion 40^a adapted to engage the lower portion of roll 39 or material thereon, which arms extend horizontally and have vertically extending rear portions pivoted to arms 41, which are, in turn, secured by suitable rivets or bolts to the bottom of the bars 22. The arms 40 are urged against the rollers 39 or the material thereon by tensile springs 42 secured to their horizontal portions and to the outer ends of arms 41.

The standards 10 have spaced apertures 10^a therein forming bearings for rods 43 carrying the rollers 44 on which the rolls of material 45 will be carried.

In operation, the material on one of the 105 rolls 45 will be drawn forwardly and will pass under the roll 32, if it be from one of the rolls 44 above said roller. If material should be drawn from one of the rolls 44 below roller 32, the material, preferably would be passed over the top of roller 32. The material is passed under the drum 20^b of the measuring device 20 and over roller 21, and over the bars 22, the member 27 and cutter disk 30 at this 110 time being at one extreme end of the bar 24. The plate 36 is now slid rearwardly to uncover the recess 13^a. The roll 39 and shaft 35 can now be lifted at the right hand end, as shown in Fig. 1, so that the halves 39^a and 39^b of roll 39 can be separated. The free edge of 115 the material is now placed between said halves and shaft 35 again dropped into recess 13^a and plate 36 drawn forwardly. The material is now held in the roll 39 so that the roll 120 can be rolled by means of crank 35^a and the material drawn forwardly. The material is accurately measured as it is drawn under the friction drum 20^b, said drum being rotated by the forward movement of the material. The 125 measuring device 20 indicates the length of 130

material drawn out and when sufficient material has been dispensed, the crank 35^a will be released. The material is thus wound on the roll 39 and is held in compact form thereon by the arm 40. When the crank 35^a is released therefore the material will not spring back and bulge at the roll 39. The operator now grasps the member 27^a and moves the same across the bar 24. The material is quickly and neatly cut by the shearing action of disk 30 against one of the bars 22 and the desired length of material thus severed. The material can now be tied with a string, the plate 36 moved rearwardly and shaft 35 raised from recess 13^a and drawn from the bearing in the arms 13 at the left of Fig. 1, when the material can be withdrawn from roll 39 and said roll and shaft 35 again placed in position. The measuring device can be raised out of operative position when desired by engaging the inner portion of rod 17 in recess 19^a. The specific structure of the measuring device forms no part of the present invention and is separately claimed in applicant's co-pending application, Serial Number 71,365, filed November 25, 1925. The cutting disk 30 is maintained always in position to be traversed for cutting the material by action of the springs 26 engaging bar 24. When desired, the members 14 can be disengaged from pin 15 and the arms 13 and parts carried thereby may be swung down to vertical position.

From the above description it is seen that applicant has provided a very simple and efficient dispensing and cutting device for flexible sheet material. The device may efficiently be used with the rack shown in applicant's Patent No. 1,462,349 granted July 17, 1923, or may be used with any suitable standard carrying the rolls of material. The device is quite simple and easily and inexpensively made. The same has been amply demonstrated in actual practice and found to be very successful and efficient.

It will, of course, be understood, that various changes may be made in the form details, arrangement and proportions of the device without departing from the scope of applicant's invention, which, generally stated, consists in a device capable of carrying out the objects above set forth, in the novel parts and combinations of parts disclosed and defined in the appended claims.

What is claimed is:

1. A device for dispensing metal screen material having in combination, a frame including spaced substantially horizontally extending arms, a pair of bars extending between and supported by said arms, said bars having adjacent edges at their tops, the space

between said bars being open at the bottom, a disk cutter movable longitudinally of said bars and having its lower portion disposed between and in engagement with said bars, one side of said cutter engaging one of said adjacent edges in shearing relation, means for guiding said disk cutter along said bars in both directions, means for yieldingly holding said cutter in engagement with said bars, means for supporting a roll of said screen material at one side of said bars, and means for drawing said screen material under the said bar, whereby said cutter may be moved across said screen material and the latter cut.

2. A device for dispensing metal screen material having in combination, a frame including spaced substantially horizontally extending arms, a pair of bars extending between and supported by said arms, said bars having adjacent edges at their tops, the space between said bars being open at the bottom, a revoluble disk cutter having its lower portion disposed between and in engagement with said bars and having one side flat and disposed against one of said bars in shearing relation, means for supporting said cutter and guiding the same for movement in both directions longitudinally of said bars for holding the same yieldingly in engagement therewith.

3. A device for dispensing metal screen material having in combination, a frame, a cutter bar extending thereacross, a member supported on said frame and extending longitudinally of said cutter bar above the same across said frame, a cutter frame guided on said member for movement in either direction, a revoluble disk cutter mounted in said frame moving in shearing relation with said cutter bar, guide rollers journaled in said cutter frame at each side of said cutter disk and engaging the under side of said member, and means for yieldingly moving said member toward said cutter bar.

4. A device for dispensing metal screen material having in combination, a frame having spaced vertical members, a pair of arms pivoted respectively to said vertical members and adapted to depend in vertical position, means for holding said arms in substantially horizontal position, means on said vertical member for holding a roll of said screen material, cutting means supported by said arms and extending therebetween, guiding means beneath which the screen material passes supported on said arms and means supported on said arms for drawing said sheet of screen material from said supporting means through said cutting means.

In testimony whereof I affix my signature.

CHARLES M. McCARTHY.
